(74) *Attorney, Agent, or Firm*—Pepper Hamilton LLP

(22) Filed: **May 28, 2009**

(57) **CLAIM**

The ornamental design for an exercise apparatus for performing an armless push-up, substantially as shown and described.

(51) **LOC (9) Cl.** 21-02

DESCRIPTION

(52) **U.S. Cl.** **D21/662**

FIG. 1 is a front and side perspective view of an exercise apparatus for performing an armless push-up, showing my new design;

(58) **Field of Classification Search** D21/662,
D21/668, 670, 672–674, 685, 686; 482/70–71,
482/79, 121, 130–131, 141, 147

FIG. 2 is a rear perspective view of the exercise apparatus;
FIG. 3 is a rear and side perspective view of the exercise apparatus;

See application file for complete search history.

FIG. 4 is a side perspective view of the exercise apparatus;
FIG. 5 is a top plan view of the exercise apparatus;
FIG. 6 is a bottom plan view of the exercise apparatus; and,
FIG. 7 is a front elevational view of the exercise apparatus,
shown in a folded condition about a midpoint.
